C. P. SYRSTAD

LINE HOLDER

Filed April 28, 1925

UNITED STATES PATENT OFFICE.

CARL P. SYRSTAD, OF BLOOMING, SASKATCHEWAN, CANADA.

LINE HOLDER.

Application filed April 28, 1925. Serial No. 26,563.

The invention relates to improvements in line holders and an object of the invention is to provide a simply constructed, inexpensive device which can be readily mounted on a wagon box or other agricultural implement and which will effectively hold the lines or reins and which is arranged so that the lines can be easily and quickly removed therefrom.

10 A further object is to construct the appliance so that the weight of the reins holds the jaws closed and such that any forward pull on the reins pulls the jaws more tightly closed and such that a back pull on the reins releases the jaws.

With the above more important objects in view the invention consists essentially in the arrangement and construction of parts hereinafter more particularly described, 20 reference being had to the accompanying drawing, in which:

Fig. 1 is a perspective view of the device secured to the side of a wagon box.

Fig. 2 is a rear view of the device.

25 Fig. 3 is a front view thereof.

Fig. 4 is an enlarged horizontal sectional view at 4—4' Figure 2 and showing the lines in dotted outline caught between the jaws.

30 Fig. 5 is a horizontal sectional view similar to Figure 4 with the movable jaws in the open position.

Fig. 6 is a horizontal sectional view at 6—6' Figure 2.

35 In the drawing like characters of reference indicate corresponding parts in the several figures.

Whilst I have herein shown the device as mounted on the side 1 of a wagon box, it will be readily understood that it can be 40 fastened in any convenient place to any vehicle or farm implement.

The holder comprises a body piece 2 having a downwardly extending arm or shank 3 and an upwardly extending stationary jaw 4 having an arcuate inner face and being provided at the rear edge with a vertical row of teeth indicated at 5. These teeth should not be sharp as they would mutilate the reins. The body piece is provided with a vertically extending hole 6 which receives pivotally a pin 7 extending from the lower end of a movable jaw 8. The pin is provided with a circumferential channel 9 and it is held in place by a split key 10 carried by the body piece and passing through the channel. This arrangement obviously per-

mits the movable jaw to be removed by withdrawing the key and when the key is in place prevents the withdrawal of the removable jaw whilst allowing of the rotation of 60 the same.

The forward side of the movable jaw presents a curved face 11 and a vertical row of teeth 12 is formed at the edge where this curved face and the rear face of the jaw 65 intersect. The teeth 12 are, in the closed position of the jaw, directly opposite those 5 but are spaced therefrom to provide a vertical slot 13 in which the reins are caught between the jaws. It will be observed that 70 the movable jaw has the ends terminating in guards 14 and 15 which in the closed position of the movable jaw prevent the escape of the reins from the ends of the slot. The lower guard is fitted with an oil hole 16 75 which permits one to oil the pin 7. The arm or shank is provided with bolt holes 17 and 18 which permit the rein holder to be fastened in place on the vehicle or wagon box. By referring to Figure 1, it will be 80 observed that the rein holder takes an upright position on the side of the box and that it is fastened to the side of the box by bolts 19 and 20 passing through the bolt holes and into the side of the box. At this 85 time the body 2 of the holder sits on the upper edge of the box side.

When it is desired to fasten the reins, the movable jaw is turned back into the position as shown in Figure 5 and the reins are 90 entered between the jaws. The movable jaw is then closed and the reins 21 and 22 become gripped between the teeth of the jaws as shown in Figure 4. Obviously the weight on the forward ends of the reins will exert a 95 forward pulling on the reins which acts to pull the movable jaw more tightly closed. The lower guard 14 is designed so that it will strike the base of the lower jaw and limit the forward and rearward turned positions of the movable jaw. This arrangement can be best seen in Figures 4 and 5. If one desires to remove the reins or lines, he simply pulls the rear ends thereof backwardly which opens the jaws and permits 105 the lines to be raised upwardly between the same.

What I claim as my invention is:

1. A line holder comprising a body piece 110 provided with a downwardly extending attaching shank and an upwardly extending stationary jaw having a vertically extend-

- ing row of teeth formed at its rear edge, a rotary jaw opposing the stationary jaw and provided with a downwardly extending pin rotatably mounted in the body piece
- 5 aforesaid, a retaining key passing transversely through the body piece and engaged in a groove formed around the lower portion of said pin, the said rotary jaw presenting a vertical row of teeth opposing the
- 10 former teeth in the closed position of the jaws and a guard carried by the rotary jaw and engageable with the base of the stationary jaw to limit the forward and reverse rotation of the rotary jaw.
- 15 2. A line holder comprising a body piece provided with a downwardly extending attaching shank and an upwardly extending stationary jaw having a vertically extending row of teeth formed at its rear edge, a rotary jaw opposing the stationary jaw 20 and provided with a downwardly extending pin rotatably mounted in the body piece aforesaid, the said rotary jaw presenting a vertical row of teeth opposing the former teeth in the closed position of the jaws and 25 upper and lower line guards carried by the rotary jaw, the lower guard being adapted to engage with the base of the stationary jaw and limit the forward and reverse rotation of the rotary jaw.
- Signed at Radville, Saskatchewan, this 30
26th day of March 1925.

CARL P. SYRSTAD.
